APPARATUS FOR PRODUCING MINUTE ORIFICES

John R. Bowman, Pittsburgh, and Forest F. Versaw, Penn Township, Allegheny County, Pa., assignors to Gulf Research & Development Company, Pittsburgh, Pa., a corporation of Delaware

Application February 19, 1945, Serial No. 578,786

3 Claims. (Cl. 76—4)

1

This invention relates to an apparatus for reducing orifices to minute size and, more specifically, for producing minute orifices of a submicroscopic diameter for use in mass spectrometers.

Flow restricting devices have been used in mass spectrometers and similar equipment wherein a gas sample is admitted to an ionization chamber and is subjected to a stream of accelerated electrons. These devices should strongly impede the flow and for this purpose capillary tubes have been used. It is desirable that the gas be admitted through a plate or disc, but it has not been previously possible to provide a plate or disc with a hole of such extremely small diameter. The molecules of entering gas should radiate symmetrically from the introduction point and consequently the orifice should be round.

It is accordingly a primary object of this invention to provide apparatus for producing a round minute orifice in a perforated plate or disc.

Other and further objects of the invention will be apparent from the following description of the invention whereby it will be seen that the objects are attained.

In general, the invention relates to an apparatus for producing a minute orifice in a plate. More specifically, the apparatus comprises an anvil having a flat polished surface of at least as great a diameter as that of the plate which is to be provided with a minute orifice. A collar surrounding the anvil and extending beyond the face thereof retains and locates the plate. There is also provided a die which is received within and guided by the collar and which has a surface accurately flat and polished. The die is so shaped that it transmits impact forces to the plate with radial symmetry.

In the accompanying drawing:

Fig. 1 is a side view of an apparatus for making impacts on a disc positioned thereon;

Fig. 2 is a plan view of the apparatus;

Fig. 3 is a sectional view along line 3—3 of Fig. 1;

Fig. 4 is a sectional view along line 4—4 of Fig. 1;

Fig. 5 is a magnified view taken through the center of a drilled blank; and

Fig. 6 is a similarly magnified view of the completed orifice.

Parallel guide rods 10 and 11 extend vertically from a base 12 and are secured at their upper, threaded ends by a cross member 13 which is retained and secured by nuts 14 and 15. A weight 16 is mounted on the rods which guide it in vertical movement, and the weight carries a project-

2

ing hammer element 17 for delivering blows to an underlying anvil and die assembly. The anvil 18 comprises a flanged base 19 with a central upstanding portion 20 which has a flat and polished upper surface. Bolts or fillister screws 21 extend into arcuate cutout portions 22 of the flange 19 and secure the anvil to the base 12 through the medium of a collar 23 which is countersunk to receive the heads of the bolts or screws. In this manner the anvil is anchored and is prevented either from rotation or tilting.

A retaining ring 24 is adapted to slip over the end of the upright portion 20, to retain and align a disc blank 25 and a superimposed die 26 for receiving impacts from the hammer member 17.

The top surface of the die 26 is rounded so that blows which are delivered to it will be transmitted symmetrically to the disc blank. It will be understood, however, that the die may have a conical upper surface, or may be of any other geometrical shape which will cause the forces of impact to be distributed uniformly over the area of the underlying disc. The lower surface 25 of the die in contact with the disc is accurately flat and polished.

In Figs. 5 and 6 are shown magnified views of the disc 25 wherein it is shown how the orifice 28 changes under the repeated impacts from the drilled hole shown in Fig. 5 to the orifice of Fig. 6 upon successive impacts.

The invention depends upon the principle of isotropic flow of the material under impact and the capability of the material to set after each impact. Annealed fine gold has such an isotropic flow and a gold plate or disc in the center of which a hole has been made as by drilling may be subjected to successive impacts such that the hole will be made smaller without distorting its initial round shape.

In one embodiment of the invention, therefore, a fine gold disc is first rolled to a thickness of 0.010 inch and a diameter of 1.0 cm. The disc is made very smooth and flat and a hole is drilled through its center. The hole initially

should be as small as practicable, for which purpose an 0.0135 inch drill may be used, although it is preferable to use an even finer drill, such as an 0.00185 inch drill of the kind employed in making injection nozzles for Diesel engines. The disc is carefully cleaned and placed on a flat surface such as a plane piece of quartz. It is subjected to annealing by heating to a dull red heat in a muffle furnace and then allowed to cool slowly with the furnace. Desirable results may

also be obtained by heating a disc to a cherry red with a hand torch. In either case, the disc is allowed to cool slowly while in position on the flat supporting surface in order to prevent warping and distortion.

The annealed disc blank is then transferred to the accurately flat surface of the supporting portion 20 of the anvil and the annular collar 24 is slipped into position to surround it and retain the die 26. The plane surfaces of the anvil and die between which the disc is received are highly polished and great care must be observed in keeping them clean throughout the operation of reducing the disc, for as the hole approaches submicroscopic size even oil is difficult or impossible to remove from it.

The reduction in size of the orifice can be followed by microscopic examination for the first few blows that are delivered by the falling weight 16, but as the hole becomes progressively smaller its size can no longer be determined by visual inspection, and therefore must be ascertained by test. In accordance with our invention the flow of air or gas at a determined rate through the orifice is taken as a measure of its useful size. Our invention accomplishes this by subjecting one side of the orifice to reduced pressure of about 0.5 mm. of mercury, while its other side is exposed to atmosphere (760 mm. of mercury) at about 70° F. Under such standardized conditions the orifice will be found of proper size for use in mass spectrometers and other apparatus providing gaseous ion sources when air or gas will pass through it at the rate of 0.1 to 0.01 ml. per minute measured at atmospheric pressure.

The exact cross-sectional shape of the completed orifice is unknown, but it probably approximates that of a single-sheeted hyperboloid of revolution, as shown in Fig. 6.

The flow of material of the blank takes place outwardly as well as inwardly, but is so exceedingly slight that it is not affected by the retaining ring 24. The flow is inward in the neighborhood of the central hole, and decreasingly so out to about half the radius of the disc. Outside of this region the flow is outward, causing the edge surface to become slightly toroidal rather than cylindrical as it was originally. In practice the increase in diameter of the disc is not measurable.

While the above description of the invention has emphasized the preparation of a minute orifice for a mass spectrometer, the minute orifices of our invention have other uses in some of which the orifice need not be so small nor so perfectly round. For other purposes, other materials than gold which are capable of substantially isotropic flow may be used, such as, for example, alloys of gold such as gold-platinum, tin, aluminum, silver, copper, and plastics. For purposes of obtaining a somewhat symmetrical orifice, the metals mentioned should be annealed.

While the preferable operation of the apparatus of our invention has been described as successive impacts, substantial reduction in the size of an orifice may take place with a single impact. However, it is preferable that the impacts be repeated and that they be made with a comparatively light weight hammer struck with a great force such as by dropping the hammer from a great height.

The impact is preferably upon the whole surface of the plate being treated, but impact on a smaller area may result in the desired effect. In order that the hole may be round it is pref-

erable that the original hole be drilled in the exact center of a circular disc. If a plate other than a disc is used, impact should be upon a surface centered about the hole. Further, if

5 the impact is not upon the whole area of the plate, it should at least be on an area covering the hole and many times greater than the cross-sectional area of the hole to distinguish clearly from the method of making larger holes smaller, 10 used by jewelers, in which the side walls of a hole are simply broken down by the impact of a die on the side walls of a hole, or from peening operations in general.

While the invention is preferably directed to 15 the making of a minute orifice in a plate or preferably a disc, the making of minute orifices in blanks of other shapes is contemplated, such as the making of small orifices for use as spinnerets in the manufacture of artificial fibers. The 20 spinneret may be a disc or a thimble. In the case of a thimble or other similar shape, the impact should take place against a surface conforming in shape. Thus, the term "plate" as used in the claims is intended to include a flat piece of material including discs, as well as various shapes which may be formed from a plate.

From the foregoing it will be understood that 30 our invention provides an apparatus for producing minute orifices, of a size smaller than can be drilled, by the application of impact applied to the surface of a pierced plate having suitable flow characteristics.

What we claim is:

35 1. Apparatus for producing a minute orifice in a plate which is preliminarily formed with a small opening, comprising an anvil having an enlarged base and a central upstanding portion the upper face of which is flat and polished, a 40 collar mounted on the central upstanding portion, fastening means extending through the collar and through cutout portions of the base to anchor the anvil and prevent it from either rotating or tilting, a ring closely fitting the upstanding portion and slidable thereon to rest on said collar and to project above the upper face of said upstanding portion, a die retained within said ring for delivering impacts to a 45 perforated plate positioned on the polished face of the anvil, said die having a flat polished under surface and a protuberant upper surface of geometrically symmetrical shape whereby impact forces are transmitted to the plate with radial symmetry in the area surrounding the perforation therein.

50 2. Apparatus for reducing an orifice in a plate to minute size, comprising an anvil having an enlarged base and a central upstanding portion the upper face of which is flat and polished, a 55 collar mounted on the central upstanding portion, fastening means extending through the collar and through cutout portions of the base to anchor the anvil and prevent it from either rotating or tilting, a ring closely fitting the upstanding portion and slidable thereon to rest on said collar and to project above the upper face of said upstanding portion, a die retained within said ring for delivering impacts to a perforated plate positioned on the polished face of the anvil, said die having a flat polished under surface and a protuberant upper surface of conical shape whereby impact forces are transmitted to the plate with radial symmetry as the perforation therein is reduced to minute size.

70 3. Apparatus for producing a minute orifice in

a perforated plate, comprising an anvil having an enlarged base and a central upstanding portion the upper face of which is flat and polished, a collar mounted on the central upstanding portion, fastening means extending through the collar and through cutout portions of the base to anchor the anvil and prevent it from either rotating or tilting, a ring closely fitting the upstanding portion and slideable thereon to rest on said collar and to project above the upper face of said upstanding portion, a die retained within said ring for delivering impacts to a perforated plate positioned on the polished face of the anvil, said die having a flat polished under surface and a protuberant upper surface of a spherical shape whereby impact forces are transmitted to the plate with radial symmetry in the area surrounding the perforation therein.
